[57] CLAIM

The ornamental design for a container lid, as shown and described.

DESCRIPTION

FIG. 1 is a right front isometric view of a container lid showing my new design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a right side elevational view thereof, the left side view being a mirror image.

The broken line showing of the container in FIG. 1 is for illustrative purposes only and forms no part of the claimed design.
